UNITED STATES PATENT OFFICE.

WILLIAM G. DUNHAM, OF CHICAGO, ILLINOIS.

CAR-AXLE-BOX LID.

No. 839,922.

Specification of Letters Patent.

Patented Jan. 1, 1907.

Application filed October 30, 1905. Serial No. 285,016.

To all whom it may concern:

Be it known that I, WILLIAM G. DUNHAM, a citizen of the United States, residing at Chicago, in the county of Cook and State of Illinois, have invented certain new and useful Improvements in Car-Axle-Box Lids; and I do hereby declare the following to be a full, clear, and exact description of the invention, such as will enable others skilled in the art to 10 which it appertains to make and use the same.

My present invention relates to car-axle-box lids of the character set forth and broadly claimed in my Letters Patent No. 15 803,155, issued October 31, 1905, entitled "Car-Axle-Box Lid," and it consists of the novel devices and combinations of devices hereinafter described, and defined in the claims.

20 The invention is illustrated in the accompanying drawings, wherein like characters indicate like parts throughout the several views.

Referring to the drawings, Figure 1 is a 25 view principally in side elevation, but with some parts sectioned and others broken away, illustrating my invention as applied to a car-axle box. Fig. 2 is a vertical section taken approximately on the line $x^2 x^2$ of Fig. 30 1, some parts left in full. Fig. 3 is a section on the same line as Fig. 2, but showing the lid turned into its open position; and Fig. 4 is a detail in section on the line $x^4 x^4$ of Fig. 1, some parts being removed.

35 The numeral 1 indicates the axle-box, and the numeral 2 a portion of the axle. The box in line with its mouth-opening is formed with a transversely-extended upwardly-projecting fulcrum-rib 3 and with a pair of outwardly-projecting laterally-spaced bearing-lugs 4, which, as shown, are cast integral with the said rib 3. These lugs 4 have aligned 40 perforations 5, and one thereof is slotted at 6 for a purpose which will presently appear.

45 The lid 7, which is preferably constructed of malleable iron and is bulged outward at 8 and inward at 9, is formed at its extreme upper edge with a semicylindrical fulcrum-seat 10, that engages and rotates upon the rounded 50 upper edge of the fulcrum-rib 3. Said lid is also formed with a perforated lug 11, that projects inward from the central por-

tion of its bulge 9. Webs 12, formed on the sides of the lid at the ends of the fulcrum-seat 10, engage with the ends of the fulcrum- 55 ribs 3 and hold the lid in working position against transverse sliding movements.

The numeral 13 indicates a bolt which is provided with a transversely-extended shaft or head portion 14, that is journaled in the 60 perforations 5 of the two bearing-lugs 4. The bolt and its head constitute what may be termed a "T-bolt," and the said head 14 is connected to the body-bolt 13 by a thin transversely-extended neck 15, and the said 65 bolt is provided adjacent to said neck with a flange 16. The free end of the bolt 13 works loosely through the perforated lug 11 of the lid, and below and outward of said lug it is provided with a stop-pin 17. A coiled 70 spring 18 is placed on the bolt 13 and is compressed between the flange 16 thereof and the said perforated lug 11.

The following important relation of the 75 parts above described should be noted. The spring 18 of the thrust device exerts a strain on a line that obliquely intersects the mouth of the box, and it finds its fixed base of reaction against the box-lugs 4 and its movable base of reaction against the perforated lug 11 80 of the lid. With this arrangement the spring exerts a force which not only tends to hold the lid closed, but which seats the lid against the mouth of the box at its upper and side portions, as well as its lower portion. 85

In all positions of the lid the spring 18 exerts a force which tends to maintain engagement between the fulcrum-seat 10 of the lid and the fulcrum-rib 3 of the box. In moving the lid from its closed position (shown in Fig. 2) into its extreme open position (shown in Fig. 3) the line of strain of said spring 18 is carried by a dead-center with respect to the axis of the bolt-head 14 and the axis of the rounded upper edge of the fulcrum-rib 95 3, and when it reaches the position shown in Fig. 3 the line of strain of said spring is below the said fulcrum-rib, so that the spring then tends to hold the lid in its open position. The extreme opening movement of 100 the lid is limited by engagement of the stop-pin 17 with the perforated lug 11 of the lid, and in this position of the lid the body of the fulcrum-seat 10 of the lid is forced off from

the rounded edge of the fulcrum-rib 3, and the lower edge only of said seat is thrown against the said fulcrum-rib, thereby reducing the leverage action of the spring 18 at 5 this time. When the lid is in its closed position, the stop-pin 17 of the bolt 13 stands slightly out of engagement with the lug 11 of the lid, so that the spring may then exert a force tending to hold the lid closed. In all 10 intermediate positions of the lid the spring 18 is compressed to a greater extent than shown either in Fig. 2 or in Fig. 3, and the stop-pin 17 is then carried farther away from the said lug 11.

15 When the lid is moved from its closed to its open position, or vice versa, the spring thrust device gradually changes its angular position, both with respect to the box and with respect to the lid, and is moved from 20 one side to the other from a dead-center, as already stated.

When the lid is in its open position, (shown in Fig. 3,) it may be removed from working position by forcing it inward, so as to carry 25 the seat 10 away from and over the rounded edge of the fulcrum-rib 3. This of course must be done against the tension of the spring 18, and a very considerable force will be required to accomplish this result. When 30 the lid is disengaged from the fulcrum-rib 3 and the stop-pin 17 is removed from the bolt 13, the spring 18 will throw the perforated lug 11 off from said bolt, and the said lid will then be entirely disconnected from 35 the box. When the T-shaped bolt 13 14 is then turned downward to an intermediate position, so that its flat neck 15 alines with the slot 6 of the lug 4, the said neck may be passed through said slot 6 by a lateral movement of said bolt, and the said bolt in this 40 way be easily removed from working position. It may of course be applied to the lugs by a reverse action. Of course, if desired, more than one of the said T-bolts and 45 coöperating springs may be employed in connection with the single box and lid, in which case the said T-bolts will be located with their shaft-like heads 14 in axial alinement.

The lid and the thrust device described 50 are of very simple construction and of small cost. They may be very quickly assembled or disconnected and have no parts that are liable to get out of order.

What I claim, and desire to secure by Letters Patent of the United States, is as follows:

1. The combination with an axle-box, of a lid hinged thereto, by means of a separable hinge permitting the lid to be lifted from the 55 box, and a spring thrust device obliquely intersecting the mouth of the box, when the lid is closed, said spring thrust device reacting against the lid and a fixed base of resistance

on the box, said spring thrust device having an angular movement both in respect to the 60 lid and the box, and exerting a strain tending to maintain engagement between the hinge members, substantially as described.

2. The combination with an axle-box, of a lid hinged thereto, by means of a separable hinge permitting the lid to be lifted from the 65 box, and a spring thrust device obliquely intersecting the mouth of the box, when the lid is closed, said spring thrust device reacting against an inwardly-projected intermediate 70 portion of the lid and a fixed base of resistance on the box, said spring thrust device having an angular movement both in respect to the lid and the box, and exerting a strain tending to maintain engagement between 75 the hinge members, substantially as described.

3. The combination with an axle-box having a fulcrum-rib above its mouth-opening, of a lid having at its upper edge a seat that engages 80 said fulcrum-rib, to form the lid-hinge, a spring thrust device obliquely intersecting the mouth of the box, when the lid is closed, and reacting against an intermediate inwardly-projecting portion of the lid and 85 against a base of resistance on the box, said spring thrust device having an angular movement both in respect to the lid and the box, when said lid is moved, substantially as described.

4. The combination with an axle-box having a fulcrum-rib above its mouth-opening, of a lid having an open seat loosely engaging 90 said fulcrum-rib, a bolt pivoted to lugs on the box and working loosely through an inwardly-projecting lug on the intermediate portion of the lid, a spring on said bolt reacting against 95 said bolt and against the lug on said lid, said bolt and spring having angular movement both in respect to the box and to the lid, said spring tending to maintain engagement between said fulcrum-rib and seat, substantially as described.

5. The combination with an axle-box and a lid connected thereto by a separable hinge, 100 said box having outwardly-projecting perforated bearing-lugs, one of which is slotted, and said lid having an inwardly-projecting perforated lug, of a T-bolt having a shaft-like head seated in the perforated bearing-lugs of said box, and having a flattened neck 105 adapted to pass through said slotted lug under a lateral movement of said T-bolt, said T-bolt being passed through the lug of said lid, and a coiled spring on said bolt compressed 110 between a collar thereon and the lug of said lid, substantially as described.

6. The combination with an axle-box and a lid hinged thereto, said box having perforated bearing-lugs, and said lid having an 115 inwardly-projecting perforated bearing-lug,

of a T-bolt having its head pivoted in the lugs of said box and having its free end passed through the lug of said lid, a spring on said bolt pressing against the lug of said lid, the thrust device made up of said bolt and spring being movable from one side to the other of a dead-center under movements of said lid, and a stop at the outer end of said

bolt, for limiting the opening movement of the box, substantially as described. 10

In testimony whereof I affix my signature in presence of two witnesses.

WILLIAM G. DUNHAM.
